UNITED STATES PATENT OFFICE.

CHRISTIAN GOTTWALD, OF CLEVELAND, OHIO.

BOILER-TUBE CLEANER.

No. 842,811.

Specification of Letters Patent.

Patented Jan. 29, 1907.

Application filed February 1, 1906. Serial No. 299,030.

To all whom it may concern:

Be it known that I, CHRISTIAN GOTTWALD, a citizen of the United States, residing at Cleveland, in the county of Cuyahoga and State of Ohio, have invented certain new and useful Improvements in Boiler-Tube Cleaners, of which the following is a specification, reference being had therein to the accompanying drawings.

10 My present invention relates more particularly to that class of boiler-tube cleaners comprising a rotary fluid-actuated motor, in combination with a suitable cutting-tool connected to and rotating with the motor, said tool being free to swing in a centrifugal manner, whereby the deposits on the interior of the tube are rapidly and effectively removed.

15 The object of my invention is to provide an apparatus with improved bearings for the rotating parts of the motor and novel means for easily adjusting or taking up the play caused by the wearing away of the bearings.

20 A further object of my invention is to provide an apparatus with positive lubrication for the bearings, a very essential point in the successful operation of motors of this class.

25 To these ends my invention consists in certain novel features, which I will now proceed to describe and will then particularly point out in the claims.

30 In the accompanying drawings, Figure 1 is a central longitudinal section through the motor. Fig. 2 is a perspective view of the cutting-tool shown detached from the motor. Fig. 3 is a sectional view taken on the line W W of Fig. 1 and looking in the direction of the arrows. Fig. 4 is a sectional view taken on the line X X of Fig. 1 and looking in the direction of the arrows. Fig. 5 is a sectional view taken on the line Y Y of Fig. 1 and looking in the direction of the arrows. Fig. 6 is a sectional view taken on the line Z Z of Fig. 2 and looking in the direction of the arrows.

40 Referring now to the drawings, 1 indicates an internal screw-thread for attaching the pipe of flexible hose which delivers the driving medium.

45 2 represents the non-rotating part of the motor, which has a diaphragm 3, through which are formed inclined passages 4 common to motors of this class.

50 5 represents a cap attached to the non-rotating part 2 by means of screw-threads 6. 55 The cap is also provided with openings 7 and separated from each other by webs 8,

which carry the journal-bearing 9. Mounted in the journal-bearing 9 and held in position by a screw 10 is a hard-metal bushing 11, provided with a flanged head 12. Within the 60 bushing 11 is rotatably mounted a hollow shaft 13, to the inner enlarged end 14 of which is attached by screw-threads 15 the rotating part of the motor 16, which latter is provided with the usual inclined passages 17. At its 65 outer end the hollow shaft 13 is provided with external screw-threads 18 and internal screw-threads 19. Attached to the journal-bearing 9 by means of screw-threads 20 is a ball-bearing cup 21, between which and another ball-bearing cup 22 is interposed a row of balls 23, which bear in circular grooves 24. A locking-nut 25 serves to hold the ball-bearing cup 22 in position, both of which engage the external screw-threads 18 on the hollow 70 shaft 13. An ordinary universal-joint connector 26 engages the internal screw-threads 19 of the hollow shaft 13, thus forming a chamber which in operation is filled with lubricating-oil and which by the action of centrifugal force is positively fed to the bearings through the small holes 27. A link 28 is attached to the connector 26 by a pin 28. The cutting-tool 29 is provided with three radially-disposed inclined wings, which latter 80 have beveled edges a b c, and said wings are spaced equidistant circumferentially of a central conical core 32, which has at its rear end a slot 30, which fits freely over the outer end of the link 27 and is attached thereto by 85 a pin 31.

The operation of the cleaner will be readily understood by those skilled in the art. The motor fluid enters at 1, passes through the passages 4 and 17 and out through the openings 7 in cap 5. As the cutting-tool is of considerably smaller diameter than the interior of the tube within which it operates, under the action of centrifugal force the tool tends to scrape the side of the tube, thereby removing whatever it comes in contact with. When the tool strikes a deposit which is not readily removed, the deposit causes the tool to rebound from side to side within the tube, which effectively breaks up such deposit, especially when of a brittle nature.

It will be seen that by my construction of a hollow shaft mounted within the comparatively long journal-bearing and held in adjustment by the exterior ball-bearing arrangement, which latter can be large and therefore a strong construction, that the apparatus is

very rigid, strong, and easily adjusted. By simply removing the cap from the front part of the non-rotating part of the motor all the parts are accessible for inspection and repairs, a novel feature of my combination.

Having thus fully described my invention, what I claim as new, and desire to secure by Letters Patent, is—

1. In a boiler-tube cleaner, the combination with a non-rotating part having a transverse diaphragm provided with inclined passages, said non-rotating part having a chamber which extends forward from said diaphragm, a removable journal-bearing mounted on the outer end of said chamber, a removable bushing secured within said journal-bearing, its rear face provided with an enlarged flange, a hollow shaft rotatably mounted within said bushing and enlarged at its rear end to conform to the enlarged flange on said bushing, a threaded rear extension on said hollow shaft to receive the rotary part of said motor, and a threaded forward extension to receive a centrifugally-acting cutting-tool, substantially as described.
2. In a boiler-tube cleaner, the combination with a non-rotating part having a transverse diaphragm provided with inclined passages, said non-rotating part having a chamber which extends forward from said diaphragm, a removable journal-bearing mounted on the outer end of said chamber, a removable bushing secured within said journal-bearing, its

rear face provided with an enlarged flange, a hollow shaft rotatably mounted within said bushing and enlarged at its rear end to conform to the enlarged flange on said bushing, a threaded rear extension on said hollow shaft to receive the rotary part of said motor, and a threaded forward extension to receive a centrifugally-acting cutting-tool, said hollow shaft forming an oil-chamber, having communicating openings to the bearings, substantially as described.

3. In a boiler-tube cleaner, the combination with a non-rotating part having a transverse diaphragm provided with inclined passages, said non-rotating part having a chamber which extends forward from said diaphragm, a removable journal-bearing mounted on the outer end of said chamber, provided at its outer end with a removable ball-bearing cup, a removable bushing secured within said journal-bearing, its rear face provided with an enlarged flange, a hollow shaft rotatably mounted within said bushing, a threaded rear extension on said hollow shaft to receive the rotary part of the motor, a threaded forward extension to receive a removable and adjustable ball-bearing cup, a locking-nut, and a centrifugally-acting cutting-tool, substantially as described.

CHRISTIAN GOTTWALD.
